TOWEL CABINET

Application filed December 19, 1925. Serial No. 76,528.

In the use of a towel cabinet, considerable time has been required to open the cabinet and place the clean towel roll therein. Generally this roll is supported on a tube forming an axis, the ends of the tube fitting within guides of the side walls of the cabinet, the walls of the guides holding the tube against lateral movement as the towel web is being unwound. These tubes when used in large quantities involve considerable expense, the rolling of the towel thereon at the laundry also takes time and some little attention on the part of the laundryman is necessary when he opens the cabinet to properly place the clean towel roll in the supporting guides.

It is also necessary or desirable when the web is wound on a tube at the laundry that it be drawn tightly so that a hard smooth roll will be formed that will keep its shape when mounted on the tube and supported in the cabinet.

The object, therefore, of my invention is to provide a cabinet that is adapted to receive a loose roll of toweling; that is, one that will rest on the floor of the chamber in which it is placed without having any supporting tube or axis and thus less time is required to load the cabinet and the roll need not be so carefully formed thereby saving time and labor at the laundry.

A further object is to eliminate wear on the web as far as possible by keeping it out of contact with the sanded feed roll, or the roll having a suitably roughened surface that is frequently used in cabinets of this type.

A further object is to provide a cabinet in which springs are eliminated and the parts are thereby reduced in number and simplified in construction.

A further object is to provide an improved locking device by means of which the feed or delivery of the clean towel web may be controlled. This locking device is designed as an improvement of a device for a similar purpose shown and described in the application of Frank M. Steiner, #49,043, filed August 8, 1925.

Other objects of the invention will appear from the following detailed description.

The invention consists in various con-

structions and combinations all as herein-after described, and particularly pointed out in the claims.

In the accompanying drawing forming part of this specification,

Figure 1 is a vertical sectional view through a towel cabinet embodying my invention;

Figure 2 is a sectional view on the line 2—2 of Figure 4 showing the locking device in its depressed position;

Figure 3 is a similar view showing in full lines the locking device in its normal position where it may be depressed by the finger of the operator;

Figure 4 is a sectional view on the line 4—4 of Figure 2; and

Figure 5 is a front elevation of the machine partially in section showing the relative position of the feed rolls, the chamber for the clean towel roll, and the locking device.

In the drawing, 2 represents the top of a suitable cabinet; 3 the side walls thereof; 4 the rear wall; and 5, a door adapted to close the front of the cabinet and which, when opened, exposes the interior thereof. This door will generally be provided with a suitable looking glass or mirror 6. 7 represents the lower wall or floor of the cabinet substantially horizontal and separated from the door 5 by a vertical opening or gap 8. A chamber 9 is provided above the floor 7 having a top wall 10 and a vertical rear wall 11 depending therefrom, and cooperating with the floor 7 to form the walls of the clean towel chamber. The wall 11 is separated from the rear of the cabinet by a passage 12 and a gap or opening 13 is provided between the forward edge of the top wall 10 and the door 5 to form a stop for the loose roll placed in the chamber 9. 15 represents a clean towel roll that is placed in the chamber 9 through the opening in the front thereof when the door 5 is opened, sufficient space being provided between the floor 7 and the top wall 10 for this purpose, the space being varied in height to accommodate rolls of different 100

diameters. This roll of clean toweling may be taken directly from the ironing machine without being tightly wound and without the use of a tube or any other form of axle and deposited by the laundry delivery man within the chamber 9 where it will lie loosely on the floor of the chamber and roll back and forth therein as the web is unwound.

Above the chamber 9 I provide a feed roll 16 having preferably a sanded or otherwise roughened peripheral surface and this feed roll has a driving connection through gears 17 with an adjacent similar roll 18 mounted, however, to revolve in the opposite direction, the gears being preferably arranged within a suitable housing 19 on the outside of the casing. The side walls of the cabinet are provided with guide slots 20 adapted to receive a spindle 21, the slots extending through 20 to the front of the cabinet so that the spindle can be easily inserted therein when the door is opened and having vertical portions extending to a point near the feed roll 18 so that the spindle 21 will slide down by gravity in the guides toward the feed roll 18. A suitable ratchet is provided in connection with the feed rolls having a dog 22 adapted to prevent backward movement of the rolls. The web of clean towel is passed up through 30 the opening 13 and around the feed roll 6 and from thence is carried down through the passage 8 to form a loop below the cabinet. The free end is then passed up through the opening 12 and around the spindle 21, and the 35 weight of the spindle and the web will hold the roll against the feed roll 18 so that when the feed roll is revolved the spindle will also be revolved and the soiled towel wound thereon proportionately as the clean portion is 40 withdrawn from the clean towel roll.

The soiled towel roll is offset or out of vertical alignment with the roll 18 so that pressure of the feed roll on the towel will force the spindle against the wall of the guide instead of raising the roll in the guide. The soiled towel is kept out of contact with the depending portion of clean web and slides on the rear wall 11 of the chamber 9, and I prefer also to provide a block 23 on the top 50 wall 10 having a rounded upper surface and mount a gate 24 above the passage 12 in position to bear on the web of soiled towel and smooth out the wrinkles and operate as a guide to feed the soiled web evenly and 55 smoothly to the soiled towel roll. Suitable tension on this gate is provided by means of a spring 25. The operator standing in front of the cabinet and pulling down on the clean web will unwind it from the roll and as the 60 feed rolls are operated, movement will be transmitted to the soiled towel roll so that a corresponding portion will be wound thereon with each operation of the clean towel feed roll.

65 In a cabinet of this type, it is desirable to

provide a locking device to prevent any careless or mischievous person from pulling out more of the clean towel than is necessary. This could easily happen if a person sees the depending clean web and pulled quickly and vigorously thereon and the result might be the dragging of the clean web on the floor and the unnecessary soiling of a portion of the towel that had not been used. To prevent such needless delivery of the clean web, I 70 provide preferably at one side of the cabinet a plate 26 on the end of the feed roll 16, having a projecting, peripherally arranged pin 27. A lever 28 is pivoted at 29 and has a finger piece 30 adapted to be pressed or operated by the user of the cabinet.

The lever pivot 29 is supported in a suitable housing 31 and is provided with a spring washer 32 to hold the lever in its adjusted positions, sufficient friction being provided between the washer and the wall of the pivot for this purpose. The lever is provided with a depending tooth 33 in the path of the pin 27 and also has an inwardly turned lug 34 which projects over the peripheral surface of the plate 26 in position to engage an outwardly projecting lug 35 formed on this plate. The lever will normally be in the position shown in full lines in Figure 3, or its locking position and the web of towel cannot be 85 withdrawn or delivered from the cabinet. A user will press down on the button 30, moving the lever to the position indicated by full lines in Figure 2, a stop pin 36 being provided to limit the downward movement of the lever. The lever will then be in the position indicated by dotted lines in Figure 3 and the user of the cabinet may then grasp the web of clean towel, pull down thereon, and unwind the towel from the roll 15, and continue 90 this unwinding movement until the pin 27 reaches a point in the revolution of the feed roll where it will contact with the tooth 33. Such contact will raise the lever 28 to its normal full line position as shown in Figure 100 3 and return the lug 34 into the path of the lug 35, and stop further unwinding of the towel roll.

105 It will be noted that this lock device permits, with each operation, a single complete revolution of the feed roll and the user of the towel can only withdraw a certain predetermined length of clean towel with each operation. This is due to the use of the pin 27 and the lug 35, the pin positively returning the 110 lever to its normal locking position where it will be engaged by the lug when the feed roll has completed its revolution.

115 In the Steiner application, above referred to, the lever having been operated once to release the roll, may again be operated and an additional length or stretch of towel obtained, or more than would be delivered with each single revolution of the feed roll.

120 In the operation of the cabinet shown here- 130

in, the user will first depress the lever 28 to the position indicated by dotted lines in Figure 3, thereby disengaging the lug 34 from the lug 35 and releasing the feed roll. He 5 may then draw down on the web of the clean 70 towel and thereupon a predetermined stretch of web will be delivered through the bottom of the cabinet in position for use. The depression of the lever 28 will bring the tooth 10 33 into the path of the pin 27 and when the pin contacts with this tooth, it will swing the lever back to the position indicated by full lines in Figure 3 and the lug 34 will be returned to the path of the lug 35 to engage 15 it positively and stop further revolution of the feed roll. The operation will then be repeated to obtain a further length of clean 20 towel.

When the feed roll is provided with only 25 one stop operating in connection with a forked member that is moved back to its locking position immediately following the initial movement of the feed roll, it is possible for a user to move the forked member 30 back to its releasing position before the feed roll completes its revolution; that is, between the period of the setting of the forked member in its locking position by the stop and the completion of revolution of the feed roll and 35 continue the feeding operation without stopping the roll.

In the present application I have eliminated this objection to the practically continuous feed of the towel without stopping the feed 40 roll by providing the pin 27 in addition to the lug 35 and located near it. When, therefore, the towel user depresses the lever 28 and releases the stop 35, the lug or tooth 33 will be moved to the dotted line position of 45 Figure 3 in the path of the pin 27 and normally this pin will engage the lug 33 and return the lug 34 into the path of the stop 35 just before the feed roll completes its revolution. If the towel user attempts to raise the lever 50 28 to clear the pin 27 just as the pin is completing its revolution, he will manually set the lug 34 in the path of the stop 35 and the time is so short between the engagement of the pin 27 with the lug 33 and the contact of 55 the stop of the feed roll with the lug 34 that the user will be unable to raise the lever to clear the pin 27 and depress it again to its release position before the stop 35 engages the lug 34 and the revolution of the feed roll 60 is completely stopped. Hence the towel user instead of being able to withdraw the towel by a practically continuous operation without stopping the feed roll, is obliged by the addition of the pin 27 to the feed roll, to allow this roll to come to a complete standstill with each revolution and thereby a considerable saving in the unnecessary use of the 65 towel is effected.

I claim as my invention:

65 1. A towel cabinet comprising an upper

compartment for the soiled toweling, and a lower compartment for the clean toweling, a door which when open opens both compartments, there being a partition between the compartments and a space between the partition and door when closed, a friction roll in the upper compartment over which the clean toweling extends between the end of the partition and the closed door, both as the clean toweling is drawn upwardly over the friction roll 70 and downwardly in its course through the bottom of the cabinet, portions of the toweling being adapted to be held in contact with each other as the toweling ascends and descends, a soiled toweling roller in the upper compartment, and a feed roll therefor geared to said friction roll, and a friction block in the rear of the cabinet over which the soiled toweling is adapted to pass and a gate normally resting thereon to straighten the toweling before 80 reaching the soiled toweling roll.

2. The combination with a towel delivery feed roll of a locking lever having an upwardly extending portion and a pivot therefor, a lug on the periphery of the feed roll and a pin in the end of the feed roll, said lever also having one end cooperating with said lug to lock the feed roll, said lever having a projection cooperative with the pin to move the locking end into position to contact with said lug and lock the feed roll.

3. The combination with a towel delivery feed roll, of a locking lever, stops mounted on said feed roll, one extending radially of the roll and the other axially thereof, said lever having lugs offset relatively one to the other and one of which has a cam surface, said lugs being adapted to engage said stops respectively, a stop on said roll being normally in engagement with its lug on said lever, the other stop being positioned to engage the cam surface of its lever lug and positively move said lever from its release to its lock position immediately preceding the completion of revolution of said feed roll.

4. The combination with a revoluble towel feeding means having stops thereon in adjacent relation, one stop projecting radially with respect to said feeding means and the other stop extending longitudinally thereof, of a locking device having lugs in off-set relation to one another to engage said stops respectively, said feeding means being normally locked by the engagement of one of said stops with one of said lugs, the manual movement of said device to a release position being adapted to disengage one lug from said stop, and a partial revolution of said feeding means being adapted to positively return it to its locking position by the engagement of its other lug with said second stop, the relative position of said stops being such that manual movement of said device to clear its lug of said second stop when said feeding means is near the completion of its stroke will posi-

tively return said first lug to its locking position and thereby check movement of said feeding means and prevent continuous feed of the towel.

5. A towel cabinet having a chamber there-in adapted to receive a supply of clean toweling, a soiled towel roller mounted in said cabinet, feed rolls for the clean and soiled portions of the towel, the web of clean towel be-
10 ing adapted to pass from said clean towel supply upwardly over its feed roll and said cabinet having a substantially horizontal wall above said chamber with a guiding edge at the front of said wall over which portions of
15 the clean web may both ascend and descend, the ascending portion being adapted to contact with the descending portion of said towel web, the rear of the cabinet having a guiding passage through which the web of soiled
20 towel is adapted to extend to the soiled towel roller and means adjacent said passage adapted to engage both sides of the web of soiled towel for smoothing and straightening it prior to its delivery to the soiled towel
25 roller.

6. A towel cabinet comprising an upper compartment for the soiled toweling and a lower compartment for the clean toweling, a door in front of both compartments, a parti-
30 tion between the compartments leaving a space between the partition and door when closed, a friction roll in the upper compartment over which the clean towel may extend after passing between the end of the partition
35 and the closed door, said cabinet having an opening in the lower portion and said toweling being adapted to pass through said space between the partition and door and through said lower opening in the cabinet, portions of
40 the clean toweling being adapted to move in contact with each other as the towel web passes upwardly and then downwardly through said space, a soiled towel roller in the upper compartment to which the toweling is
45 adapted to extend and a feed roll therefor geared to said friction roll.

In witness whereof, I have hereunto set my hand this 15th day of December, 1925.

GOTTFRID OLSON.
